UNITED STATES PATENT OFFICE.

WILLIAM PHILIP BLAKE, OF KIRKSVILLE, MISSOURI.

DISCHARGE-MEASURING DEVICE FOR LIQUID-RECEPTACLES.

1,359,661.

Specification of Letters Patent. Patented Nov. 23, 1920.

Application filed December 12, 1919. Serial No. 344,451.

To all whom it may concern:

Be it known that I, WILLIAM PHILIP BLAKE, a citizen of the United States, and a resident of Kirksville, in the county of Adair 5 and State of Missouri, have invented certain new and useful Improvements in Discharge-Measuring Devices for Liquid-Receptacles, of which the following is a specification.

10 My present invention relates generally to liquid receptacles and particularly to a discharge measuring device therefor, my object being the provision of an arrangement for measuring the discharge, as for instance, 15 in the case of dose regulation from medicine bottles.

My invention moreover, proposes a device which from its nature is capable of formation in various ways, either integral 20 with or separate from a bottle, jar and the like, and from various materials.

In the accompanying drawings illustrating my present invention,

Figure 1 is a side view illustrating a bottle 25 tilted in its initial position for discharge and equipped with my invention.

Fig. 2 is a view showing the bottle righted in the second position with a measured dose in its discharge neck,

30 Fig. 3 is a view showing the bottle in the third or dose discharge position,

Fig. 4 is a vertical section through the neck of a bottle with my improvements applied therein, and

35 Fig. 5 is a detail perspective view of the liquid separating plug.

Referring now to these figures, and particularly to Figs. 4 and 5, and bearing in mind that I have for the purpose of illustration selected that form in which the plug 40 is made separate from the neck of the bottle, even though the invention is susceptible of integral formation, I have shown a bottle at 10 with a normally stoppered discharge neck 11, the stopper of which appears at 12.

45 My invention, in the form of a plug 13, constructed of any suitable material, is arranged to interfit the neck 11 and is introduced therein and preferably located adjacent to the base of the neck or at such 50 point along the neck as will leave the desired space for a dose of the liquid contents of the bottle between the upper end surface of the plug and the stopper 12.

55 As shown, the plug is for the above reasons cylindrical and this plug is provided

with diametrically opposed lengthwise grooves 14 and 15, which when the plug is introduced in the bottle neck, form channels between the plug and the inner surface of 60 the bottle neck.

Fig. 4 in particular makes it plain that the groove 15 and the channel formed thereby are of considerably greater length than the groove 14 and the channel formed thereby, by virtue of the fact that one end of the 65 plug 13 is cut away at a considerable angle with respect to the opposite end, both of the grooves and the channels formed thereby, communicating at their opposite ends 70 with the dose receiving space above the plug and the interior of the bottle 10 below the plug.

By virtue of this construction and with the stopper 12 in place, the bottle may be 75 inclined with its neck downward and with its longer channel 15 lowermost in the position shown in Fig. 1, where the pressure of the fluid in the lower channel will force air from the space between the plug and the 80 stopper and into the bottle through the shorter channel, so that when the bottle is righted in position shown in Fig. 2, the air having been displaced from above the 85 plug 13, the liquid in the dose measuring space will be held therein, and prevented from running back into the bottle.

Moreover, when the bottle is tilted in an opposite direction, or in other words, with the short channel down and the long channel 90 up and upon removal of the stopper 12, the liquid within the dose receiving space between the plug and the stopper will be allowed free escape and the remaining fluid in the bottle at the same time held against 95 discharge.

Where the plug is formed separate from the bottle, as I have described and shown, it is obvious, that the dose receiving space may thus be readily adjusted by shifting the 100 plug lengthwise of the bottle neck, but it is to be understood that my invention in its broadest aspect contemplates that the plug which thus forms a liquid separating device and a means by which measured quantities 105 of fluid may be intermittently discharged, may be formed integral with the bottle neck, and where they are formed separate, the plug may be made of various materials suitable for the purpose.

I claim:—

1. A liquid separating device, for a liquid

5 container having a stoppered discharge neck, consisting of a permanent plug having one end cut away on an angle with respect to its opposite end and having diametrically opposed grooves extending lengthwise thereof from end to end, one of which grooves is substantially longer than the other by virtue of the said angular end of the plug, as described.

10 2. A liquid separating device for a liquid container having a stoppered discharge neck, consisting of a plug adjustably disposed within the said neck, having its outer end cut away on an angle with respect to its inner end and having diametrically opposed lengthwise grooves communicating between the spaces upon opposite sides of the plug and one of which is of substantially greater length than the other by virtue of 15 the said angular end.

15 3. A liquid receptacle having a stoppered neck and means separating its body from its said discharge neck, having channels communicating between the body and its neck 20 the said angular end.

25 at spaced points, one of which channels is of greater length than the other.

4. A liquid receptacle having a stoppered neck and means separating its body from its said discharge neck, having channels communicating between the bottle and its neck 30 at spaced points, one of which channels is of greater length than the other, said means being in the form of a plug adjustable within the said discharge neck, for the purpose 35 described.

5. A liquid receptacle having a stoppered discharge neck, and means located in the neck whereby to form a liquid receiving space adjacent to the stopper of the neck and apart from the body of the receptacle, 40 said means having channels therethrough at spaced points communicating between the said liquid receiving spaces and the body of the receptacle and one of which channels is substantially greater in length than the 45 other.

WILLIAM PHILIP BLAKE.
